R. H. Jackson,

Steam-Boiler Indicator.

N° 66,593.

Patented July 9, 1867.

WETNESSES.

J. H. Brinridge

Frank S Alden

R. H. Jackson

United States Patent Office.

R. H. JACKSON, OF SANDUSKY, OHIO, ASSIGNOR TO HIMSELF AND A. C. VAN TINE OF THE SAME PLACE.

Letters Patent No. 66,593, dated July 9, 1867.

IMPROVEMENT IN BOILER SAFETY-GAUGES.

The Schedule referred to in these Letters Patent and making part of the same.

TO ALL WHOM IT MAY CONCERN:

Be it known that I, R. H. JACKSON, of Sandusky, in the county of Erie, and State of Ohio, have invented certain new and useful improvements in Steam Boiler Safety-Gauge; and I do hereby declare that the following is a full and complete description of the construction and operation of the same, reference being had to the accompanying drawings, making a part of this specification, in which—

Figure 1 is a front view of the gauge.

Figure 2 is a side view.

Figure 3 is a top view.

Figures 4 and 5, detached sections to which reference will be made.

Like letters of reference refer to like parts in the several views.

This apparatus consists of a cylinder, A, fig. 1, to the top B of which is screwed a small or supplementary cylinder, C, in which is fitted a solid piston, indicated by the dotted lines *a*, fig. 1, and of which E is the rod. To the lower end of the cylinder A is attached a pipe, F, which reaches to the boiler G, into which it descends to the water space below the flues H, as indicated by the dotted line *a'*. This pipe is provided with a stop-valve, I, fig. 5, operated by the hand-wheel I'. From the upper end of the cylinder project the elbows J J'. To the elbow J is attached a pipe, K, which reaches to the boiler, and is projected into the same near to the top of the flues, as indicated by the dotted line *b*. This pipe is also furnished with a stop-valve, in construction like the one above referred to, and operated in the same way, by a hand-wheel, K'. To the elbow J' is attached a pipe, L, which reaches to the boiler, and opens just within the shell, as indicated by the dotted line *c*. This pipe is also provided with a stop-valve, constructed and operated in the same manner as the valves in the pipes referred to. Dependent from the under side of the top or cover of the cylinder A is a lug, M, fig. 4, from the inner side of which projects an arm, M'. In the end of this arm is pivoted a lever, N, to the long arm of which is suspended a float, N', by a rod, O. To the upper side of the arm M is fitted a slide valve, O', and which is connected to the minor arm of the lever N by a link, P, and operated by the same, as will hereafter be shown. This valve is kept down upon its seat by a spring, P', and covers a small port leading from the cylinder A into the supplementary cylinder C. Said opening is indicated by the dotted line *d*. In the drawing the apparatus is represented as being placed directly over the boiler, and immediately connected to the same by short straight pipes, but it is not a necessity that it should be placed in this position, it being shown thus simply for the convenience of illustration. The intention is to place this gauge in the pilot-house on water-crafts, some ten, twenty, or even fifty feet above the boiler, and in charge of the captain or pilot; also to be placed in the offices adjacent to stationary engines, and not left to the exclusive care of engineers, who, in case of water falling below the point of safety in the boiler, are seldom willing to make the fact known until too late. The apparatus when placed thus distant from the boiler is connected to the same by a range of pipe in such a way as the nature of the circumstances may demand. The fire-place and boiler are connected to each other by a steam pipe, which pipe is provided with a stop-valve, and is connected by means of a chain or rod to the end of the piston-rod referred to as being in the cylinder C.

Having thus indicated the construction of the apparatus, and its relation to the boiler, the practical use and operation of the same are as follows:

The boiler on being filled up with water to the usual level, and steam generated, water will be forced up into the cylinder A, through the pipes F and K, thereby raising the float N', and closing the port communicating with the cylinder C by the valve O'. So long as the water in the boiler is above the point of danger the port remains closed, but as soon as it falls below that point, or on a level with the top of the flues or crown-sheet, and hence below the end of the pipe K, and which is the point of danger, steam is admitted into this pipe K, through which it passes into the cylinder A, forcing the water back into the boiler through the pipe F; in consequence the float falls and opens the port, through which steam rushes up into the cylinder C, the piston in which is thereby pushed up, and opens the valve in the pipe by which the boiler and fire-place are connected, as above said, and through which pipe water from the boiler rushes into the furnaces and extinguishes the fires. The boiler on being again filled to its proper level and the steam exhausted from the cylinder A, the float

therein will rise up by the water flowing into it from the boiler, in the manner as above described, and thereby will close the port α by the valve O' , and thus shut off the communication between the two cylinders, which will again be opened in case of danger in the same way as before instanced. When there is no steam up, and hence no pressure on the boiler, the water in the cylinder A will fall back into the boiler, thereby preventing the adhesion of the valve O' to its rest. The purpose of the valve I is to gauge or regulate the amount of water to flow into the cylinder A, and, if required, shut off all communication with the boiler.

What I claim as my improvement, and desire to secure by Letters Patent, is—

1. The pipes K, F, and L, as arranged in combination with the cylinders A and C, and boiler G, for the purpose and in the manner described.

2. The valve O' , when arranged and operated by the lever N and float N', when in the relations to the piston α substantially as and for the purpose set forth.

R. H. JACKSON.
